UNITED STATES PATENT OFFICE.

MAX JACOB, OF, BERLIN, GERMANY, ASSIGNOR TO THE NATIONAL CASH REGISTER COMPANY, OF DAYTON, OHIO, A CORPORATION OF OHIO, (INCORPORATED IN 1906).

ATTACHMENT FOR CASH-REGISTERS.

1,123,302. Specification of Letters Patent. **Patented Jan. 5, 1915.**

Application filed March 29, 1911; Serial No. 617,595.

To all whom it may concern:

Be it known that I, MAX JACOB, a subject of the Emperor of Germany, residing at Berlin, in the Kingdom of Prussia and Empire of Germany, have invented certain new and useful Improvements in Attachments for Cash-Registers, of which I declare the following to be a full, clear, and exact description.

This invention relates to cash registers and has more particular relation to that class of registers which is designed to make a printed record of all transactions entered in the machine.

The improvements, for the sake of illustration, are shown as applied to a machine of the type shown and described in Letters Patent of the United States granted to Thomas Carroll on March 8, 1904, and numbered 754,049, and reference may be had to said patent for a more detailed description of a machine of that type.

It is customary to provide, in cash registers adapted to certain classes of business, a printing mechanism for printing the amount of the transaction upon a sales slip or sheet which is first made out by a clerk and then inserted in the machine for the purpose of receiving the printed entry. Machines have also been designed to print the different items of a transaction, such items being printed on different lines of a sales slip. In machines of the latter type, it has generally been found difficult to provide means whereby the printing of the detail amount on the proper line of the slip is insured. It has been customary to provide a long printing table on which the sales slip is laid, the table being marked with an index for the guidance of the operator, so that the slip might be laid in the proper position to receive an impression thereon in the proper line. It will readily be seen that in a hasty operation, the operator may not place the slip in proper alinement with the index and the impression would therefore be out of alinement with the lines on the slip.

It is one of the objects of the present invention to provide means whereby the printing of the amounts in the proper line is insured and it is a further object of the invention to provide mechanism compelling the

adjustment of the slip to a position in which the printing may be effected.

With these and incidental objects in view the invention consists in certain novel features of construction and combinations of parts, the essential elements of which are set forth in appended claims and a preferred form of embodiment of which is hereinafter shown with reference to the drawings which accompany and form part of this specification.

Figure 1 is an end view of the machine showing the general printing mechanism, the cabinet being removed for the sake of clearness. Fig. 2 is a sectional view of a portion of the printing mechanism showing the platen operating means and the means for controlling the positioning of the printing table. Fig. 3 is a detail view of the releasing means for the detent mechanism of the amount keys and of the controlling keys of the printing table. Fig. 4 is a detail of one form of sales slip which may be used in connection with the present invention. Fig. 5 is a detail cross section view of the printing table showing the connections for returning the table to normal position.

In a machine of the type to which the present improvements are shown as applied, it is customary to provide several banks or rows of keys each comprising a series of keys 20, which, when depressed, are adapted to control the positioning of the differential mechanism common to a machine of this type. Such differential mechanism is of a form well known in the art and no detailed description will be given herein as it forms no part of the present invention and reference may be had to the above United States Letters Patent for such detailed description if desired. As is also usual in this type of machine, the positioning of the differential mechanism effects the positioning of a series of printing wheels 21 which are adapted to print on a sales strip a detailed record of each transaction as entered upon the machine. Each of the printing wheels 21 is provided with two sets of raised printing type 22, each set running from "1" to "9" and "0," the corresponding numbers of each set being arranged on said printing wheel 21 in diametrically opposite positions. This ar-

angement is well known in the art and is for convenience in taking two impressions from the wheel at the same time. In the present machine it will readily be seen that 5 an impression is taken from the upper point of the wheel 21 by a platen roller 23, such impression being made on a detail strip 24 of well known form, which is led from a supply roller 25, about the platen roller 23 10 and thence to a receiving roll 26.

In the use of the present improvements the sales slip is adapted to be inserted beneath the printing wheel 21 and just above a platen 26 carried by a sliding block 27 15 which receives its sliding movement from an operating lever 28. Pivoted connected to the lever 28 is a pitman 29 bifurcated at its upper end to straddle a shaft 30 and carrying an anti-friction roller 31 playing 20 in a groove 32 formed in a box cam 33. The box cam 33 is adapted to receive one complete rotation at each operation of a crank handle 34, through the medium of intermediate gears 35, 36, 37 and 38. It will thus 25 be seen that at each operation of the register, the platen 26 will receive a single reciproca- 22 on the inserted sales slip.

The sales slip, shown in Fig. 4, is shown 30 as arranged for use by a co-operative association and is adapted to receive thereon, im- 35 pressions indicating a total balance of an ac- count of a certain subscriber up to a certain date and from then on the detail totals of 35 different transactions as they may occur. The slip is further provided with a space 40 near its bottom edge for receiving impres- 45 sions indicating the total of all the entries shown on the slip. Across the right hand half of the slip there is arranged a series of 45 lines 39 which are numbered from 1 to 15 running from the top to the bottom of the slip, these lines being adapted to receive any desired written entries concerning the print- 50 ed entries of transactions, which entries are to be printed just to the left of the line num- 55 ber as shown by the several sample entries indicated on the slip.

The slips are inserted in a movable print- 50 ing table or slip carrier 40 which is adapted 55 to slide in guide ways 41 and 42 formed in the casing of the machine. On its underside the table 40 is provided with a rack bar 43 meshing with a pinion 44 mounted on a stub 55 shaft 45. Connected at 46 to the pinion 44 is a spring 47 which at its other end is connected to the stub shaft 45. The purpose of this spring is normally to retain the printing table in its rear position. The table 40 60 is provided with a handle 48 which is adapted to be grasped by the operator for the purpose of sliding the table to different positions so as to bring any particular line on the sales slip in alinement with the type 22

on the wheels 21 from which the impression 65 is to be taken.

For the purpose of controlling the position- 70 ing of the table 40 and of properly alining the table in adjusted position, there is provided a series of depressible keys 49. 75 These keys 49 are adapted to slide in a frame 50 and are normally held in elevated position by springs 51 interposed between pins 52 carried by the keys and a rigid part of the frame 50. At their lower ends the keys 75 are cut away to form bevel projections 53 which projections, on the depression of any one of the keys, serve to cam a detent plate 54 forward until the key is fully depressed, when the plate 54 will be spring drawn rear- 80 ward to cause the plate to engage in a notch 55 of the depressed key. When any one of the keys 49 is depressed, its lower end 56 will be in the path of a locking bar 57 carried by a leaf spring 58 mounted on the underside of 85 the forward end of the sliding table 40. The bar 57 is formed on its upper side with the bevel edge 59, and when the table 40 is drawn forward after a key 49 has been de- 90 pressed, the bar 57 will pass under the lower end 56 of the depressed key and will then engage the key to prevent a return of the table 40 to normal position. In its upper side the table 40 carries a bar 60 which is adapted to engage the depressed key on its 95 rear side and the table will thus be locked in adjusted position by reason of the engage- 100 ment of the bar 60 on the rear side of the key and the bar 57 on its forward side. The table is then held in adjusted position until the depressed key 49 is released and allowed to resume its normal upper position. Upon the releasing of the table 40 it will be re- 105 stored to its normal position by the spring 47 as above described.

The releasing of the keys 49 is effected by forcing the detent plate 54 forward to dis- 110 engage it from the notch 55 of the depressed key. The forward movement of the plate 54 is effected by a link 61 pivotally connected at 62 to the plate 54 and at its rear end to a lever 63 which is pivoted at 64 and carries at its upper end an anti-friction roller 65, adapted to be acted upon by a cam 66, which cam receives a single actu- 115 ating rotation at each operation of the ma- chine.

In order to compel an adjustment of the table 40 at each operation of the machine, means are provided for locking the machine 120 against movement until the table is moved out of normal position. This locking mech- anism comprises a bell crank lever 67, the upper arm of which is normally in the path of a pin 68 carried by the cam 33 while the 125 lower end extends rearwardly and normally rests upon the table 40. Upon the movement of the table 40 to one of its adjusted posi-

tions, the rear end of the table will pass from under the lower arm of the bell crank 67, thus permitting the spring 69 to rock the bell crank lever 67 about its pivot 70 to withdraw the upper arm of said lever from the path of the pin 68.

In a machine of the type shown in the above patent, each of the keys 20 is usually provided with a bevel lug 71 adapted to co-10 operate with a bevel notch 72 formed in a detent 73 which is adapted to hold the key in depressed position. The holding of a key in its depressed position is effected in the following manner. When a key is depressed, its beveled lug 71 will, as above stated, engage the notch 72 formed in the detent 73 and upon the continued depression of the key the detent 73 will be elevated to withdraw its lower end 74 out of the path 20 of a shoulder 75 formed on a locking plate 76 which is normally spring drawn toward rear position. When the end 74 of the detent is thus withdrawn from shoulder 75 the plate 76 will move rearward to cause said shoulder 25 75 to pass beneath the detent and thus hold it in elevated position and consequently hold the operated key in depressed position.

As it is sometimes desirable to release a key after it has been depressed and before 30 an operation of the machine is had, for the purpose of correcting an error, means are provided for manually releasing the depressed keys independent of an operation of the machine. This releasing means comprises a hand lever 77 rigidly mounted on a rocking shaft 78. A pin 79 is mounted on the shaft 78 and is adapted to engage a pin 80 carried by the plate 76 so that upon the rocking of the shaft 78 by the lever 77, the plate 76 will be drawn forward to disengage the shoulder 75 from the detent and thus permit the detent and the depressed key to return to normal position. As one of the keys 49 may be depressed through error it is 45 also desirable to provide means for releasing such a depressed key independent of an operation of the machine and mechanism is therefore provided in connection with the release lever 77 for releasing the depressed key 49 simultaneously with the release of the depressed keys 20. This means comprises a pin 81 carried by lever 77 and adapted to engage a bifurcation formed in one arm of a bell crank lever 82 pivoted at 83, the other 50 end of which lever is adapted to engage a notch 84 formed in the detent plate 54. It will thus be seen that when the lever 77 is pressed down to release the depressed keys 20, it will also effect a rocking of the lever 82 and thus draw the detent plate 54 forward to disengage the detent from the notch 55 of a depressed key 49.

The printing wheels 21 may comprise the usual amount wheels and also wheels for

making a printed record of the initial of the 65 clerk making the sale and likewise some designation to indicate the style of the transaction, such for instance as "Charge", "Received on account" "Paid out" or "No sale". Printing wheels may likewise be 70 provided for printing the date of the transaction, but as the operation of such additional wheels is well known in the art no detailed description of the setting mechanism therefor will be given herein, as they form 75 no part of the present invention.

The operation of the machine is as follows: In using a slip such as shown in Fig. 4, the operator will ascertain by reference to the slip just which line is to receive the 80 printed entry and will then insert the slip in the slidtable table 40 and depress the key 49 appropriate to the desired line. He will then grasp the handle 48 and draw the table forward until it engages and becomes locked 85 to the depressed key. He will then depress the keys 20, representing the transaction, and turn the operating crank handle 34. This will effect an operation of the general mechanism of the machine and the printing 90 of the amount in the proper line on the sales slip and finally the release of the table to permit of its restoration to normal position. If, however, after he has depressed all the keys and positioned the table, he determines that an error has been made in setting up the transaction, all that is necessary 95 for him to do is to depress the lever 77. The depressing of the lever will release the depressed keys 20 and likewise the depressed 100 key 49, thus permitting a restoration of the table 40 to normal position under the action of its restoring spring 47. The new and correct transaction may then be set up in the regular manner.

While the form of mechanism herein shown and described is admirably adapted to fulfil the objects primarily stated, it is to be understood that it is not intended to confine the invention to the one form of embodiment herein shown and described but that it is susceptible of embodiment in various forms all coming within the scope of the claims which follow.

What is claimed is:—

1. In a cash register, the combination with means for printing items of record, of a manually movable record material carrying table capable of differential adjustment from the same position at every operation of the machine to cause a printing of the items of record at any point on the record material, and manipulative means operable independent of any movement of said table for predetermined the extent of such adjustment 120 to be permitted.

2. In a cash register, the combination with means for printing items of record, of a

- manually movable record material carrying table capable of differential adjustment from the same position at every operation of the machine to cause a printing of the items of record at any point on the record material, and a plurality of keys operable independent of any movement of said table and adapted when operated to predetermine the extent of such adjustment to be permitted.
10. 3. In a cash register, the combination with means for printing items of record, of a printing table capable of differential adjustment relative to said printing means, a series of keys for determining the extent of such adjustment, and latching means carried by the table and coöperating with the keys to latch the table in adjusted position.
4. In a cash register, the combination with means for printing items of record, of a printing table capable of differential adjustment relative to said printing means as a preliminary to an operation of the register, latching means for holding the table in its position of adjustment during a printing operation, means effective at the end of such operation to disable said latching means to permit of a restoration of said table to normal position and means for so restoring said table at the end of such operation.
30. 5. In a cash register, the combination with means for printing items of record, of a printing table capable of adjustment relative to said printing means, keys for controlling the extent of such adjustment, latching means for holding the table in its position of adjustment during a printing operation, means effective at the end of such operation to disable said latching means, and spring means for restoring the table to normal position.
6. In a cash register, the combination with a main operating mechanism, of means for printing items of record, a printing table capable of manual adjustment relative to said printing means, a series of keys operable independent of said printing table for predetermining the extent of adjustment to be permitted, means for locking said printing table in adjusted position, a lock for the operating means effective when the printing table is in normal position, and means controlled by said operating means for disabling said latch for the table.
55. 7. In a cash register, the combination with a main operating mechanism, of means for printing items of record, a printing table manually adjustable relative to the printing means, a series of keys operable independent of said table to predetermine the extent of adjustment to be permitted, means for latching the printing table in adjusted position, a bell crank lever, one arm of which normally rests on said table while the other obstructs movement of the operating mecha-
- nism so that the operation of the main operating mechanism is prevented until the table is moved from its normal position, and means controlled by the main operating mechanism for disabling the latching device of the table.
8. In a cash register, the combination with a main operating mechanism, of means for printing items of record, a printing table manually adjustable relative to the printing means, a series of keys operable to predetermine the extent of adjustment of the said table, latching devices for holding the table in adjusted position, means controlled by the table for locking such operating mechanism when the table is in normal position, and means controlled by the operating mechanism for disabling the latching device of the table.
9. In a cash register, the combination with means for printing items of record, of depressible keys for controlling the adjustment of the printing means, detent means for holding said keys in depressed position when operated, a printing table adjustable relative to the printing means, a second set of depressible keys for controlling the adjustment of the table, detent means for holding any one of said second set of keys in depressed position when operated, and a single means operable independent of an operation of the register to actuate both of said detent means to release their respective keys.
10. In a cash register, the combination with means for printing items of record, of a printing table capable of differential adjustment relative to said printing means, a series of keys for determining the extent of such adjustment, latching means carried by the table and coöperating with the keys to latch the table in adjusted position during a printing operation, means effective at the end of such an operation to destroy the co-operative relation between said latching means and keys, and spring means for restoring the table to normal position.
11. In a cash register, the combination with means for printing items of record, of a printing table capable of adjustment relative to said printing means, a series of depressible keys for determining the extent of such adjustment, means for latching an operated key in depressed position, latching means carried by the table and coöperating with a depressed key to latch the table in adjusted position during a printing operation, and means effective at the end of such an operation to release the depressed key to permit of a restoration of said table to normal position.
12. In a cash register, the combination with means for printing items of record, of a printing table capable of adjustment relative to said printing means, a series of de-

pressible keys for determining the extent of such adjustment, means for latching an operated key in depressed position, latching means carried by the table and co-operating with a depressed key to latch the table in adjusted position during a printing operation, means effective at the end of such an operation to release the depressed key to permit of a restoration of said table to normal position, and means for automatically restoring said table at the end of such operation.

13. In a cash register, the combination with means for printing items of record, of a manually movable record material carrying table capable of differential adjustment to cause a printing of the items of record at any point on the record material, manipulative means operable independent of any movement of said table for predetermining the extent of such adjustment, and a latching device carried by said table and adapted to co-operate with said manipulative means to hold the table in its position of adjustment during a printing operation.

14. In a cash register, the combination with means for printing items of record, of a manually movable record material carrying table constructed to retain the record material in the same position relative thereto at every operation of the machine and capable of differential adjustment to cause the printing of items of record on any desired line and in a column, and manipulative means, operable independently of any movement of said table, for predetermining the extent of adjustment of said table so that the desired line may be brought into printing position.

15. In a cash register, the combination with means for printing the items of record, of record material having marks indicating the positions of the items to be printed, a manually movable table constructed to retain the record material in the same position on the table at every operation of the machine and capable of differential adjustment to cause the printing of items at the mark indicating the desired position, and manipulative means for predetermining the extent of such adjustment so that the record material may be brought into such a position that the item may be recorded at the desired mark.

16. In a cash register, the combination with means for printing items of record, of a manually movable record material carrying table constructed to retain the record material in the same position on the table at every operation of the machine and capable of differential adjustment to cause the printing of the items at any desired point on the record material and in a column, and a plurality of keys for predetermining the

extent of such adjustment so that the desired point may be brought into printing position.

17. In a cash register, the combination with means for printing items of record, of a manually movable record material carrying table capable of differential adjustment to cause a printing of the items of record at any desired point in a column on the record material, and manipulative means for predetermining the extent of such adjustment so that the desired point whether before or after the previous recorded item may be brought into printing position.

18. In a cash register, the combination with means for printing items of record, of a manually movable record material carrying table capable of differential adjustment to cause a printing of the items of record at any point in a column on the record material, and manipulative means, operable independent of any movement of said table, for predetermining the extent of such adjustment to be permitted so that the desired point whether before or after the previous recorded item may be brought into printing position.

19. In a cash register, the combination with means for printing items of record, of a manually movable record material carrying table capable of differential adjustment to cause the printing of the items of record at any point in a column on the record material, and a plurality of keys operable independent of any movement of said table and adapted when operated to predetermine the extent of such adjustment to be permitted so that the desired point on the record material whether before or after the previous recorded item may be brought into printing position.

20. In a cash register, the combination with means for printing items of record, of a manually and slidably movable record material carrying table capable of differential adjustment to cause a printing of the items of record at any point in a column on the record material, and manipulative means operable independent of any movement of said table for predetermining the extent of such adjustment to be permitted.

21. In a cash register, the combination with means for printing items of record, of a manually and slidably movable record material carrying table capable of differential adjustment to cause a printing of the items of record at any point in a column on the record material, and a plurality of keys operable independent of any movement of said table and adapted when operated to predetermine the extent of such adjustment to be permitted.

22. In a cash register, the combination with means for printing items of record, of

a printing table capable of being moved differentially at right angles to the printing line and from the same position at each operation of the machine, and a series of keys for predetermining the extent of such adjustment.

23. In an accounting machine the combination with means for printing items of record, of record material capable of limited movement at an angle to the printing line, and manipulative means for controlling the extent of movement of the record material.

24. In an accounting machine the combination with means for printing items of record, of a record material carrying table capable of a limited movement at an angle to the printing line, and manipulative means for controlling the extent of movement of said table.

25. In an accounting machine the combination with means for printing items of record, of record material capable of manual limited movement at an angle to the printing line, and a series of keys for controlling the extent of movement of the record material.

26. In an accounting machine the combination with means for printing items of record, of a slip carrying table constructed to hold the slip from movement relative thereto and adapted to be moved a limited extent at an angle to the printing line, and manipulative means for determining the extent of movement of said table.

27. In a cash register, the combination with means for printing items of record, of a printing table capable of differential adjustment relative to the printing means, and a series of keys constructed to obstruct movement of the table and thereby determine the extent of adjustment of the table.

28. In a cash register, the combination with means for printing items of record, of a printing table capable of adjustment relative to said printing means, a series of de-

pressible keys for determining the extent of such adjustment, means for latching an operated key in depressed position, latching means carried by the table and coöperating with the depressed key to latch the table in 50 adjusted position during a printing operation, means effective at the end of such an operation to release the depressed key to permit of restoration of said table to normal position, and means independent of the operation of the register for releasing the depressed key before the operation of the machine also to permit such restoration. 55

29. In a machine of the class described, the combination, with type carriers, of an operating mechanism, a record material supporting table capable of differential adjustment relative to the type carriers as a preliminary to an operation, means for retaining the table in any of its adjusted positions, 60 means whereby an operation of the operating mechanism will disable said retaining means, and means automatically restoring the table to non-adjusted position upon disabling the retaining means. 70

30. In a machine of the class described, the combination with type carriers, of an operating mechanism, a record material supporting table capable of differential adjustment relative to the type carriers, manipulatively controlled means for retaining the table in any of its adjusted positions, means whereby an operation of the operating mechanism will disable said retaining means, means operable independently of said operating mechanism for disabling said retaining means, and means automatically restoring the table to non-adjusted position upon disabling the retaining means. 75 80

In testimony whereof I affix my signature 85 in the presence of two witnesses.

MAX JACOB.
